UNITED STATES PATENT OFFICE

LEON LAURENT, OF ST. JUNIEN, FRANCE

MACHINE FOR SHARPENING OF SAWS

Application filed February 5, 1929, Serial No. 337,693, and in France February 6, 1928.

The present invention relates to machines for sharpening saws by an artificial grindstone, and is characterized by the utilization of reproducing cams or templates presenting a more or less elongated shape of the upper part of the tooth to be reproduced, and effecting the raising of the grindstone-support exactly at the moment of the advance of the saw-tooth, in such manner, that the grindstone affecting the upper part of the tooth to be sharpened, describes during raising, above the tooth a curve determined by the cam-section.

Different other features will be put forward in the following description referring to the annexed drawings, which represent diagrammatically in the way of example, an embodiment of the machine.

Fig. 1 is a front view of the machine;

Fig. 2 is a lateral view, if looking in the direction of the arrows 2-2 of Fig. 1;

Fig. 3 is a plan view of the grindstone-support, the axis of rotation of the grindstone being removed into the horizontal plan;

Fig. 4 is a plan view of a pressing device;

Fig. 5 shows a rider destined for regulation in accordance with the distance of teeth;

Figs. 6 to 8 refer to details.

The artificial grindstone 1 is carried, together with the driving pulleys 2, by a support 3 stirrup-like and pivoting freely at its extremity 3' between studs or the like 35, 35' around an axis z-z (Fig. 3) parallel to the axis of rotation of the grindstone, in such manner that the latter axis is always displaced parallelly to itself.

The studs 35, 35' are supported by a bow 36 which can be fixed in any angular position around the axis y-y by means of a bolt 37, upon a fixed body 38.

The grindstone-support 3 is provided with a suspension-bracket 39 attached to the lower extremity of a rod 4 by means of a double articulation 40, 41 forming a cardan-joint.

This suspension rod 4 is provided at its

upper extremity 4' with a threaded spindle 5 serving for the regulation of the lowering of the grindstone 1. The lower end of this spindle 5 bears in one of three cups 6, 6', 6" of a movable arm 7 pivoting around an axle 8 provided in the frame 9.

An extension 10 of this frame supports one or several rollers 11 guiding and supporting a cam-support 12 carrying a reproducing cam 13 of appropriate profile corresponding to the curvature of the tooth to be obtained, the cam being fixed, for example, by means of a screw 14 in a vise 15.

For the manufacture of such cams 13 wood will be found very suitable as it permits the making of said cams by the person using the machine; a few seconds will suffice to replace one cam by another so that the machine will be adapted without groping about, for a novel toothing.

The arm 7 reposes on the cam-support 12 through the medium of a roller 16.

A lever 17 pivoting around an axle 18 controls simultaneously: At one part, a pusher or tappet provided with a palet 19 and articulated at 20; its length can be regulated by a screw 19' and its function is to advance the saw S; At the other part, the cam-support 12 articulated at 21 to this lever 17 and the latter is arranged to impart to this support an alternating and essentially rectilinear movement (assuming that the arc described by the extremity 21 of the lever is replaced by a straight line).

The lever 17 receives its oscillating motion from an oscillating arch 24 through the medium of a connecting rod 22, whose one extremity 43 is articulated to the lever 17 and the other extremity 42 to a rider 23 adjustably mounted on the arch 24 for movement lengthwise thereof. The rider has a set screw 24^a by means of which the rider may be secured to the arch at any desired adjustment.

The arch may be oscillated by any suitable means such as an eccentric or the like, step 90

pulleys being provided for variation of speed. The bow 24 oscillates around an axis 25 in the direction of the arrow F (Fig. 5) from the position A represented in full lines, up to the position B represented with dotted lines, the lever 17 being thereby oscillated in the direction of the arrow F' around its axis 18.

The saw blade S (Figs. 1 and 4) is maintained during its advance by a pressing shoe 26 articulated at the end of an arm 27 swinging around a vertical axle 28 (Fig. 4) and applied toward the saw by a spring blade 29 abutting against a stud 30 of the arm 27 and maintained by the wings 31 of a counter-plate 32 movable with the spring 29 around an axle 32.

The lever 27 with its pressing shoe 26 articulated to the said lever applies itself perfectly against the saw notwithstanding its thickness, the flexibility of the spring being regulated by a rider 33 movable in a slide 34 of the counterplate 32.

The working of the device is readily to be understood.

The pusher with palets 19, acted upon by the lever 17, advances the tooth of the saw μ and the template 13 introduces itself below the roller 16 of the pivoting arm 7 at the moment when the upper part of the tooth to be sharpened is situated opposite to the grindstone 1 which describes during its raising, as said before, a curve determined by the section or shape of the template 13.

As soon as the advance of the tooth is finished, the tooth is sharpened whereupon the lever 17 moves backwardly and carries with it the template-support 12 and the driver 19. The latter articulated at 20 engages the next tooth μ' , whilst the grindstone 1, whose supporting bracket 3 oscillates freely between the studs 35, 35', descends by its own weight and sharpens the front part t of the tooth, procuring to the same the appropriate cutting angle, the bracket 3, 3' being for this purpose adjustable angularly around the axis $y-y$.

Fig. 6 shows the shape α of the teeth to be obtained and Fig. 7 illustrates two sections of the template, b , b' reproducing these teeth.

The length of the reproducing cam or template 13 is of course determined according to the differences of strokes of the driver or shifter 19 and of the template-support 12, these strokes being proportionate to the distance separating them from the axle 18 of the lever 17.

It is possible to obtain with the same template 13 (whose shape is determined in accordance with the shape β γ of the given tooth) all required distances e between the teeth.

The regulation is effected for this purpose by the displacement of a rider (23) along the bow 24 oscillating around its axis 25.

In the extreme position B of the bow 24 (see the dotted lines in Fig. 5, corresponding to the end of the sharpening of a tooth), which corresponds to the position γ , viz. the one at the end of the stroke of the template 13, and supposing that the rider 23 is fixed at a point C nearest to the oscillation axis 25, the extremity 42 of the connecting rod 22 coincides owing to the design with this axis 25, in such manner that the backward movement 75 of the lever 17, when considering its movement from the extreme position 17_B in the sense F'_1 , is zero, the bow 24 being inactive with regard to the said lever.

If, on the contrary, the rider 23 occupies 80 the extreme position D, the stroke of the lever 17 is the greatest.

Now, the extreme advanced position 17_B is invariable, independently of the regulation of the rider 23, owing to the fact, that if the bow occupies this extreme advanced position B, the center ω of the arc of the circle 24 coincides owing to the design with the extremity 43 of the link 22 at the point of its articulation upon the lever 17; hence it follows that the link or connecting rod 22 will be always radial in this position B, with regard to the arc 24, notwithstanding the adjustment of the rider 23, and that this adjustment is without any influence upon the extreme advanced position 17_B of the lever 17.

Summing up it will be seen that the lever 17 is controlled in such manner that its forward stroke (in the sense F') terminates always into the same extreme position 17_B , 100 whilst an eventual increase of the stroke (in order to vary the distance between the teeth of the saw) is produced at the backward movement (sense F'_1). Hence it is possible to obtain the same shape of the tooth, β γ , and different distances e without any displacement whatever of the template 13.

In such case, the action of the support 12 upon the roller 16 precedes (and completes) the one of the reproducing template 13. 110 Fig. 8 shows that the action of this support extends itself from α to β and that the action of the template takes place from β to γ , which point is immutable.

It is of course possible to obtain a whole range of intermediate strokes for the lever 17 and hence for the template 13 by the regulation of the position of the rider 23 upon the arc 24, viz. changing the position from C to D.

These different devices permit to employ rationally several working speeds of the lever 17 (for example 30, 40 and 50 strokes in the minute) and hence several advance speeds for the saw S, the duration of sharpening being in each case proportionate to the distance between the teeth; a tooth having the pitch of 3 mm. needs less time for sharpening than a tooth, the pitch of which is equal to 90 mm.

The machine obtained is hence a universal one, sharpening in a perfectly rational way the teeth with small and great pitches between them and presenting the following advantages:

- (a) rapidity and facility of the adjustment for the required distance, the adjustment being effectable either during stopping or during the working of the machine;
- 10 (b) a continuous alternating, oscillating movement of the lever 17;
- (c) an advance movement terminating always into the same position 17_B.

The grindstone is, as was shown, adjustable with regard to its lowered position, by the screw 5.

Finally, it is possible to obtain by the same template teeth of different depth, according as to whether the screw 5 engages the 20 cup 6 or 6' or 6'' of the lever 7, whereby the distance of the axle 8 from said screw is modified.

The invention is of course not limited to the embodiment shown and described as the 25 same permits very numerous modifications without departing from the general invention idea.

It is for example possible to obtain an equal result by a fixed reproducing template 30 or the like, upon which travels a roller, like 16, acting upon the grindstone-support. Hence it may be stated, in general way, that the template or the like at one part and the means controlling the grindstone at the other 35 part are performing, relatively to each other a rectilinear alternating movement.

Furthermore, the suspension bracket 39 can be attached to the bow 3 at any point 40 intermediate between the extremity 35 of this bow and the grindstone 1; in such case, since the grindstone-support is established according to the principle of a lever of the 3rd kind (pivoting at one extremity, application of the force to an intermediate point) the 45 height of the template or the like is established or determined according to the ratio between the arms of levers 1—35 and 39—35.

What I claim, is:

1. In a machine to sharpen the saw-teeth, 50 a controlling lever, means on said lever to advance the saw b'' a pitch after each sharpening, and means to secure an invariable extreme advanced position of said lever and to increase the eventual backward stroke of 55 the same, a grindstone, a template to raise it, and means to connect said template to said lever, to permit sharpening of saws with equal teeth and different pitches.

2. In a saw sharpening machine, a grind- 60 stone, an arm in which said grindstone is mounted for rotation, said arm being mounted for universal angular adjustment, supporting means for the free end of said arm, including a vertically movable member for 65 raising and lowering the free end of the arm

and hence also the grindstone; an oscillatory lever, a longitudinally movable cam supporting member operated by said lever and on which the weight of said vertically movable member is imposed a pivotally mounted 70 lever which bears on the longitudinally movable cam supporting member, an adjusting element with which the vertically movable member is provided and which adjusting element bears and is shiftable longitudinally on said pivotally mounted lever to vary the amplitude of vertical movement of the grindstone without changing the gage or position thereof, a cam on said cam supporting member, and means for moving a saw step by step 75 for operation upon by the grindstone.

3. A machine for setting the teeth of a saw, including a control lever, means actuated by said lever to feed the saw a predetermined distance after each setting, a grindstone, a cam corresponding with the shape of the saw teeth and the spacing thereof, means connecting said cam with said lever for operation thereby, a rocking arc actuating said lever, a runner shiftable on the rocking arc, a rod connecting said lever with said runner and pivotally connected to each of them, the said arc when in its most forward position being concentric with the pivotal connection between the rod and the lever, so that the 90 advance stroke of the lever is invariable under all adjustments of the runner to effect variations of the amplitude of movement in the return stroke of the lever.

4. A saw sharpening machine as claimed in 100 claim 2, including a segment member pivotally mounted for rocking movement, an element shiftable on said segment member and a rod pivotally connected to said shiftable element and also pivotally connected to said lever, the said segment member when in its most forward position being concentric to the pivot by which the rod is connected to the lever, so that the point defining the limit of the forward, feed stroke, of the lever, is in- 105 variable at all adjustments of said shiftable element.

In witness whereof I affix my signature.
LEON LAURENT.
